UNITED STATES PATENT OFFICE.

RUDOLPH W. GOEB, OF ST. LOUIS, MISSOURI, ASSIGNOR TO THE CONTROLLER COMPANY OF AMERICA, OF ST. LOUIS, MISSOURI, A CORPORATION OF MISSOURI.

COIN-CONTROLLED LOCKING MECHANISM.

SPECIFICATION forming part of Letters Patent No. 772,799, dated October 18, 1904.

Application filed July 11, 1904. Serial No. 216,112. (No model.)

To all whom it may concern:

Be it known that I, RUDOLPH W. GOEB, a citizen of the United States, residing at the city of St. Louis, State of Missouri, have invented 5 a certain new and useful Improvement in Coin-Controlled Locking Mechanisms, of which the following is a full, clear, and exact description, such as will enable others skilled in the art to which it appertains to make and use the 10 same, reference being had to the accompanying drawings, forming part of this specification, in which—

Figure 1 is a front elevation, a portion of the casing being broken away and the front 15 wall of the casing being removed. Fig. 2 is a transverse sectional elevation on about the line 2 2 of Fig. 1. Fig. 3 is a top sectional view on about the line 3 3 of Fig. 1. Fig. 4 is a fragmentary side elevation on about the 20 line 4 4 of Fig. 1, and Fig. 5 is a top plan view.

This invention relates to improvements in coin-controlled locking mechanisms, being particularly applicable as a telephone-lock.

25 My object is to provide an efficient structure for locking a telephone against use by an unauthorized person, the structure being of such character that the telephone can be released through the instrumentality of a deposited coin or token, while the deposited coin or token can, when desired, be returned to the depositor and the telephone can be released by central without the necessity of depositing a coin.

30 To these ends and also to improve generally upon mechanisms of the character indicated the invention consists in the various matters hereinafter described and claimed.

Referring now more particularly to the 40 drawings, 2 (see Fig. 5) indicates the receiver suspension-hook of a telephone, (not shown,) and 3 indicates the receiver adapted to be supported upon and removed from said hook in a well-understood manner. A box or casing 45 4 is suitably supported in proximity to the telephone, as by being connected to a wall or other support in a manner which is well known and well understood, said casing containing

the hereinafter-mentioned locking mechanism and being provided with a coin-slot or race-way 6.

Pivoted within the casing is a lever-plate 8, which has an arm 9 extending through a vertical slot 7 in the front wall of the casing, said arm being adapted to extend above and across the receiver suspension-hook 2, as indicated in Figs. 2 and 5, so that when the lever-plate 8 is locked the said arm 9 serves to lock the receiver suspension-hook against upward movement. The said arm 9 will therefore be hereinafter referred to as the "main" locking element. Extending rearwardly from the lever-plate 8 and formed upon said plate is a finger 100, whose upper surface forms a support for the hereinafter-mentioned locking-arm, while the body portion of the lever-plate forms a shoulder 101 with said rearwardly-projecting finger.

Pivotedly supported within the casing and at substantially right angles to the said lever-plate 8 is a locking-lever 10, having a coin-receiving-arm 11 extending in proximity to the before-mentioned raceway 6, so that said arm can be engaged by a deposited coin, said lever 10 also having a locking-arm 12 and a stop-arm 14. The said coin-receiving arm 11 is upon one side of said pivotal point of said lever 10, and the said locking-arm 12 and stop-arm 14 are upon the other side of said pivotal point. Said arm 12 normally rests upon the upper surface of the before-mentioned supporting-finger 100 upon the lever-plate 8, said locking-arm lying close to and in rear of the before-mentioned shoulder 101. Therefore when this locking-arm is in its normal position just indicated the lever-plate 8, with its arm 9, is locked against movement, and the receiver suspension-hook 2 is consequently locked against movement. An arresting-finger 102 projects from said lever-plate 8, and when the parts are in the normal positions just described said arresting-finger lies intermediate the locking-arm 12 and the stop-arm 14 and in the path of movement of said stop-arm 14. The parts being in their locked and locking positions above indicated,

when a coin is deposited into the raceway 6 it engages the coin-receiving arm 11 and rocks the lever 10 until the stop-arm 14 engages the arresting-finger 102. This movement of the locking-lever 10 is not sufficient to disengage the coin-receiving arm 11 from the coin and to thus permit the coin to proceed down the raceway 6, but the arresting of the locking-lever 10, by reason of the engagement of the stop-arm 14 with the arresting-finger 102, causes the coin-receiving arm 11 to remain in the path of the coin and to thus continue to support the coin, the movement of the locking-lever before being arrested having been sufficient to carry the locking-arm 12 out of locking position with relation to the lever-plate 8. The coin thus serves to hold the locking-lever in unlocking position until the lever-plate 8 rocks into position to unlock the receiver suspension-hook 2, such locking of the lever-plate 8 and its arm 9 occurring when the receiver 3 is removed from the suspension-hook and the spring commonly acting upon said hook forces the same into raised position, as is well known in telephone construction. As soon as the lever-plate 8 is rocked by the receiver suspension-hook the arresting-finger 102 moves backwardly out of the path of movement of the stop-arm 14, and the weight of the coin, which has up to this time been resting upon the coin-receiving arm 11, serves to further rock the locking-lever 10 to throw the coin-receiving arm 11 out of the path of movement of the coin to permit said coin to proceed farther down the raceway 6. As soon as the coin passes the arm 11 the locking-arm 12 falls (being upon the heavier side of the lever 10) and comes to rest in unlocking position upon the upper surface 103 of the lever-plate 8. When the receiver 3 is replaced upon the hook 2, said hook descends in the customary manner, and the forwardly-extending portion of the lever-plate 8 and its arm 9 being the heavier portion said lever-plate rocks forwardly to re-assume its locking position, the upper surface 103 of the lever-plate being thus carried from under the locking-arm 12 of the locking-lever 10 and said locking-arm falling into its locking position, as indicated in Figs. 1 and 4, when the receiver suspension-hook reaches its normal position, supporting the receiver.

Preferably mechanism is provided with what I shall term a "locking-out" device for the purpose of preventing the main locking member 9 from returning to locking and locked position until the receiver (having been removed) has been replaced upon the suspension-hook. This locking-out device comprises an arresting-plate 19, pivoted within the casing and having an arresting portion 22, adapted to be brought beneath a suitable portion of the lever-plate 8, (such as the downwardly-extending finger 104,) when said arresting-plate

is rocked, as hereinafter described. An arm 20, extending from said arresting-plate, projects across the receiver suspension-hook 2 beneath the same, and a spring 15, acting upon the arresting-plate 19, tends to rock said plate 70 into position to throw its arresting portion 22 beneath the before-mentioned finger 104 upon the lever-plate 8. When the parts are in normal position, the receiver engages the said arm 20 and holds the same against the 75 force of the spring 15 in such position that the arresting portion 22 of the arresting-plate 19 is in rear of the said finger 104, as illustrated in Fig. 4. As the receiver is removed from the suspension-hook and said suspension- 80 hook rises, thus rocking the lever-plate 8, as has been heretofore described, the spring 15 rocks the arresting-plate 19 to throw the arresting portion 22 into arresting position beneath the said finger 104, the arm 20 being 85 thrown outwardly toward the end of the receiver suspension-hook in a manner which will be apparent. Thus while the receiver is off the suspension-hook this suspension-hook can be depressed in order to attract central's 90 attention, (as is well understood,) but the lever-plate 8 and its arm 9 cannot rock sufficiently to carry the supporting-surface 103 from under the locking-arm 12, and thereby permit said locking-arm to drop into locking position, 95 for the downward movement of the lever-plate 8 is limited by reason of the engagement of the finger 104 upon the arresting-plate 22. When, however, the receiver is replaced upon the hook, said receiver engages 100 the said arm 20 and throws the arresting-plate 19 out of arresting position, so that when the receiver suspension-hook falls, with the receiver upon it, (which in the usual use of a telephone occurs only after the conversation 105 has been completed,) the parts will be returned to their locked and locking positions. Pivoted in proximity to the coin-chute or raceway 6 is a coin-returning lever 53, having at its lower end an inclined coin-support 56, which lies below said coin-chute in position to support a coin deposited in said chute. The delivery-raceway 51, leading to the exposed coin-cup 52 upon the outside of the casing, lies below this coin-support 56, 115 so that upon rocking of the lever 53 to carry it from beneath a coin supported thereon such supported coin falls into the delivery-chute and rolls into the cup 52, from which it can be taken by the depositor. An electromagnet 59 co-operates with an armature 58, carried by said coin-returning lever 53, so that upon energization of said magnet the said armature is attracted and the said lever is rocked to carry the coin-support 6 from beneath the coin and to permit the coin to be discharged into the delivery-raceway, as previously described. Pivoted upon the coin-receiving arm 11 of the locking-lever 10 is a 120 coin-arresting pin 105, which extends into the 130

coin-raceway 6, as indicated in Figs. 1 and 2, said pin being of such length that when the locking-lever is in its normal locking position a sufficient space is left between the lower 5 end of the pin and the coin-support 56 to permit the passage of a coin, while when the locking-lever 10 is in unlocking position, with its locking-arm 12 resting upon the upper surface 103 of the lever-plate 8, said pin is so close to the said supporting-plate 56 that a coin cannot pass between the said plate and the end of the pin, and thus be discharged from the coin-raceway into the till or coin-receptacle 106. Therefore after a deposited 10 coin has left the coin-receiving arm 11 and has thus thrown the locking-lever into unlocking position, said lever having come to rest in unlocking position, with its locking-arm 12 resting upon the surface 103 of the lever-plate 8, the coin falls upon the coin-support 56 and is prevented by the pin 105 from leaving the raceway. If it be desired to return the coin to the depositor, it is only necessary for central to energize the magnet 59, 15 whereupon the coin-returning lever 53 is locked, as has been previously described, and the coin drops into the delivery-raceway 51. If, however, the desired connection has been secured and the coin is not to be returned to 20 the depositor, when the receiver is replaced upon the suspension-hook and the locking-lever 10 returns to its normal locking position, as has been previously described, the coin-arresting pin 105, rising with the coin-receiving 25 arm 11, moves from coin-arresting position, and the coin rolls from the coin-support 56 into the till. It will be noted that this mechanism provides for returning to the depositor the particular coin which he has deposited and that the coin last deposited is discharged into the coin-receptacle as soon as the telephone is out of use, so that a coin is supported upon the support 56 only between the 30 time at which the coin is deposited and the time at which the depositor completes the use of the telephone.

The present structure also includes mechanism for enabling central to release the locking mechanism without the use of a deposited 50 coin, so that when a subscriber is called the mechanism will be released and the depositor can use the telephone. To this end a releasing-lever 18 is suitably pivoted in the casing, as upon the bracket 107, one end of this releasing-lever being in connection with the coin-returning lever 53, as by passing through an opening in a lug or finger 108 upon said coin-returning lever. The upper end of the said releasing-lever has an inclined surface 109, 55 the arm 11 of the locking-lever 10 lying in the path of movement of said inclined surface 109 of said releasing-lever when said lever is rocked in one direction, and behind said inclined surface the finger 110 of said releasing-lever is provided with a notch 111,

adapted to receive the said coin-receiving arm 11 of the locking-lever.

When the parts are in normal position, the releasing-lever lies out of the path of movement of the locking-lever, as indicated by 70 Figs. 2 and 3. Should central desire to release the telephone, however, as when calling a subscriber, the magnet 59 is energized as when a coin is to be returned to the depositor. This rocks the coin-returning lever 53, as has been heretofore described, and the rocking of said coin-returning lever serves to lock the releasing-lever 18. When the inclined end 75 109 of the finger 110 engages the coin-receiving arm 11 of the locking-lever, it rides upon said coin-receiving arm, depressing the same and rocking the locking-lever, the arm 11 of the locking-lever then returning into the notch 111 of the arm 110 of the releasing-lever. The releasing-lever is thus prevented 80 from returning to normal position until the locking-lever has been again sufficiently rocked to carry its coin-receiving arm out of the said notch. When the coin-receiving arm 85 of the locking-lever rests in the said notch of the releasing-lever, the locking-arm 12 of said locking-lever lies above the shoulder 101 of the lever-plate 8 and is in line with the inclined surface 112 at the rear face of said lever-plate. The locking mechanism is thus 90 held unlocked, and as soon as the receiver is removed from the suspension-hook the suspension-hook rises in the usual manner and raises the main locking-arm 9, thus rocking 95 the lever-plate 8. In this rocking of the lever-plate the cam-surface 112 engages the locking-arm 12 of the locking-lever and elevates said locking-arm, thus depressing the coin-receiving arm 11 sufficiently to carry the same out of the notch 111 of the releasing-lever, 100 whereupon the releasing-lever and the coin-returning lever fall into their normal positions. The locking-arm 12 then falls upon the surface 103 of the lever-plate 8, and the parts are in the same positions in which they 105 would be had a coin been deposited and the receiver 3 removed from the suspension-hook.

I am aware that minor changes in the construction, arrangement, and combination of the several parts of my device can be made 110 and substituted for those herein shown and described without in the least departing from the nature and principle of my invention.

Having thus described the invention, what is claimed as new, and desired to be secured by 115 Letters Patent, is—

1. In a coin-controlled locking mechanism, the combination with a movable locking device having a locking-arm and a stop-arm, of a movable main locking element, and an arresting-finger upon said main locking element, said arresting-finger lying intermediate said locking-arm and said stop-arm co-operating 120 with the latter, the movement of said main locking member serving to carry said arrest- 125

ing-finger into and out of the path of movement of said stop-arm; substantially as described.

2. In a coin-controlled locking mechanism, 5 a movable main locking member, a pivoted arresting-plate lying in a plane at substantially right angles to the plane of said main locking member, an arresting portion upon said plate adapted to move into and out of the 10 path of movement of a coöperating part upon said main locking member, means tending to force said arresting-plate into arresting position, and an arm upon said arresting-plate and adapted to be engaged by a telephone-re- 15 ceiver; substantially as described.

3. In a coin-controlled locking mechanism, a coin-receiving raceway, a main locking member, a movable locking element coöperating therewith and having a coin-receiving arm, a 20 coin-arresting device for preventing a coin from leaving said raceway after it has left said coin-receiving arm, means for returning such arrested coin to the depositor, and means whereby said coin-arresting device is operated 25 upon operation of said locking member; substantially as described.

4. In a coin-controlled locking mechanism, a main locking member, a locking element coöperating therewith and having a coin-receiving arm, a coin-raceway, a coin-support, means for returning a coin from said support to the depositor, a coin-arresting device for arresting a coin upon said support, means whereby said arresting device is in coin-arresting position when said movable locking member is in unlocking position, and means whereby said coin-arresting device is out of arresting position when said locking member is in locking position; substantially as described.

40 5. In a coin-controlled locking mechanism, a main locking member, a movable locking element coöperating therewith, a support for a deposited coin, a coin-arresting device connected to and movable with said locking element, and serving to hold the coin upon said coin-support, and means for returning a coin upon said support to the depositor; substantially as described.

6. In a coin-controlled locking mechanism, 50 a main locking member, a movable locking element coöperating therewith, a coin-receiving raceway, a coin-delivery raceway, a movable coin-support intermediate said raceways and obstructing passage from said receiving-raceway to said delivery-raceway, there being 55 a discharge from said support into a till, and

a coin-arresting device connected to and movable with said locking element and adapted to obstruct said discharge from said coin-support; substantially as described.

60

7. In a coin-controlled locking mechanism, a main locking member, a coin-support, means for returning a coin from said support to the depositor, a coin-arresting device for arresting a coin upon said support, and means whereby when said main locking member is in locking position said arresting device is out of arresting position, while when said main locking member is in unlocking position said arresting device is in arresting position; substantially as described.

65

8. In a coin-controlled locking mechanism, the combination with a main locking member, of a movable locking element coöperating therewith and having a locking-arm which rests upon said main locking member when the latter is in unlocking position, whereby said locking element is prevented from returning to locking position while said main locking member is in unlocking position, a 75 coin-support, means for returning a coin from said support to the depositor, and a coin-arresting device adapted to hold a coin upon said support and connected to and movable with said locking element; substantially as de- 80 scribed.

70

9. In a coin-controlled locking mechanism, a movable locking element, a releasing mechanism therefor, a coin-returning mechanism, and a single operating member controlling 90 both said releasing mechanism and said coin-returning mechanism; substantially as described.

85

10. In a coin-controlled locking mechanism, a movable locking element, a movable coin- 95 returning device, a releasing member for said locking element, and connection between said releasing member and said coin-returning device; substantially as described.

90

11. In a coin-controlled locking mechanism, 100 a movable locking element, a coin-returning lever, and a releasing-lever coöperating with said locking element and operatively connected to said coin-returning lever; substantially as described.

105

In testimony whereof I hereunto affix my signature, in the presence of two witnesses, this 5th day of April, 1904.
